UNITED STATES PATENT OFFICE.

CHARLES D. SEEBERGER, OF YONKERS, NEW YORK.

CONVEYER.

977,047.

Specification of Letters Patent. Patented Nov. 29, 1910.

Continuation of application filed August 18, 1905, Serial No. 274,807. This application filed April 9, 1906, Serial No. 310,587. Renewed April 25, 1910. Serial No. 557,591.

To all whom it may concern:

Be it known that I, CHARLES D. SEEBERGER, a citizen of the United States, residing at Yonkers, in the county of Westchester and State of New York, have invented certain new and useful Improvements in Conveyers, of which the following is a specification, reference being had therein to the accompanying drawings.

10 My present invention relates to certain improvements in landings for use with conveyers, and is designed to produce a stationary landing upon which the passenger can be discharged from the moving conveyer 15 without any possibility of his being tripped or overthrown.

In carrying out my invention I employ in connection with a stationary rigid landing formed by or rigidly secured to the stationary structure, an intermediate float which is capable of the slight vertical movement which may be necessary between it and the stationary landing, against one end of which its end abuts, and which is also controlled by 25 the conveyer so that there will be no gap between its receiving edge and the tread surface, thereby preventing any possibility of shoe soles, skirts, etc., catching or wedging between the tread surface and the receiving 30 edge of the float as the passenger is discharged upon the float.

My invention is further concerned with the same float, provided with means whereby its vertical position with relation to each 35 step as it passes beneath it is accurately determined in advance by the step itself, so that when the step reaches the receiving end of the float, it will be at just the right height to exactly coöperate with the step.

40 To illustrate my invention, I annex hereto two sheets of drawings in which the same reference characters are used to designate identical parts in all the figures, of which—

Figure 1 is a central longitudinal section 45 through the upper end of the ordinary type of moving stairway showing my invention applied thereto: Fig. 2 is a side elevation of the body portion of three steps detached, with my invention applied thereto; and Fig. 50 3 is a top plan view of the same but with the wheels and tracks also shown.

The steps 5 are of the customary construction, such as are shown in my application No. 79,520, filed October 22, 1901, being

mounted upon the wheels 6, which roll upon the customary tracks 7, the steps being connected by the rack links 8 with which the driving spur gear 9 meshes in the customary manner to advance the steps as power is applied to the spur gear.

Of course it will be understood that I do not confine my invention to the employment of the particular form of steps shown and method of driving them, and in some features I do not confine it to the employment 65 of steps at all, as a continuous tread or carrying surface might be employed instead of the separate steps shown.

The steps 5 are in the same horizontal plane at the upper end to form the moving 70 landing at the upper horizontal portion, which landing may be of any desired length, varying from a fraction of a step to the several shown, and before they pass around the end 10 on their return movement, they pass 75 beneath the stationary portion 11 of the landing which consists of a plate supported at its sides or far end, or both, from the stationary structure in which the moving stairway is mounted.

Interposed between the stationary landing and the tread surfaces of the steps forming the moving landing is the float 12, which consists of a thin plate extending across the tread surfaces of the steps, and preferably 80 having its forward edge beveled. This plate or float rests at its receiving edge upon the tread surface of the step beneath it, and may be held by any suitable mechanism which permits it to have a slight vertical movement 90 to accommodate itself to steps whose horizontal tread surfaces are on slightly different levels, and by which it is held from any material longitudinal displacement. I preferably control the movements of the plate 12 by pivoting it at both sides to the parallel links 13 and 14, whose other ends are suitably pivoted by means of the rods 15 to the brackets 16 supported in the frame-work outside of the tracks 7. This mounting of the float will be readily seen to permit of the slight vertical movement thereof that may be necessary to accommodate it to steps having tread surfaces of different heights while preventing any possibility of its being 100 displaced far enough longitudinally to interfere with its functions.

As shown in Fig. 2, the receiving edge and

the bottom of the rear end of the float are preferably slightly below the level of the under side of the main portion of the float. With this arrangement, in the event that the 5 step beneath the main portion of the float is higher than the one its receiving edge is over, a clearance is provided for such higher step so that the front edge of the float will not be lifted up and cause a gap thereat. 10 Preferably, however, I provide mechanism whereby each step controls the position of the forward edge of the float so that as the step passes beneath said forward edge the latter will be at a proper height to just permit 15 the clearance of the step and prevent the possibility of anything that is likely to be in the vicinity from getting between the step and the float. For this purpose, I secure to the arms 13 the arms 17, preferably 20 forming them integral therewith, whose outer ends are provided with contact points, preferably taking the form of anti-friction rollers 18; and upon the side brackets 19 of each step, I adjustably secure the controlling 25 plates 20, which may be conveniently secured, so as to be vertically adjustable, by the set screws 21 passing through slightly elongated vertical slots 22 formed therein and taking into the brackets 19. From a 30 consideration of the relation of these parts as shown in Fig. 2, it will be apparent that just prior to the time that the forward edge of any step reaches the adjacent edge of the float the anti-friction rollers 18 will strike 35 the controlling plates 20 which have been carefully adjusted for each step at such a distance below its tread surface that when the forward edge of the step reaches the edge of the float, the latter will be elevated to 40 just the right height to permit the clearance of the step without producing a gap. The reason for employing this mechanism is the fact that it is very difficult to get the tread surface of each step at exactly the same 45 height above the rails, and by providing the adjustable controlling plates, the desired accuracy can be secured more readily and certainly than by depending on the accurate manufacture of the steps. These controlling 50 plates may be extended, if desired, as indicated in dotted lines at 23 in Fig. 2, so that they extend entirely across the step, and so that the float is at all times controlled by the height of the passing steps. 55 In case the controlling mechanism is not employed, and the receiving edge of the float is allowed to rest on the tread surfaces of the steps, I bevel off the forward edge of each step a trifle, as indicated in dotted lines 60 at 24 in Fig. 2, so that in case a step with a high tread surface should follow a low one, the receiving edge of the float will not catch on the forward edge of such following step, as would necessarily occur if it were not 65 beveled off.

To do away with the noise caused by the friction of the float on the steps, I may balance it, so that it is suspended with little or none of its weight resting on the steps to cause friction by pressure. A convenient 70 means of doing this is to extend the arm 13 below its pivotal point 15, as at 25, and mount thereon an adjustable sliding weight 26, held by a set screw 27, so that the desired amount of weight or pressure can be 75 accurately regulated.

The above described float is of especial advantage in the comparatively short movable landing I have shown, and it will be apparent that it is of still greater use in the 80 still shorter landings which may be employed, and in those forms of conveyers in which the landing is practically dispensed with, as the object of the movable landing is to afford the passenger an interval of 85 time in which he may leave the conveyer after reaching the top of the incline. If a long movable landing is employed, he has plenty of time to think, and naturally steps off carefully before the end of the movable 90 landing is reached. If on the other hand, the movable landing is very short, or practically dispensed with, he has but little time to think, and it becomes essential to employ a safety device, such as the float, which prevents any possibility of his being caught by any gaps, etc., and insures his landing safely 95 no matter how inattentive he may be.

While I have shown my invention as embodied in the form which I at present consider best adapted to carry out its purpose, it will be understood that it is capable of modifications, and that I do not desire to be limited in the interpretation of the following claims, except as may be necessitated by 105 the state of the prior art.

This application is filed in lieu of, and in continuation of my co-pending application Serial No. 118,049, filed August 2, 1902, renewed August 18, 1905, Serial No. 274,807, 110 which I shall abandon, without of course abandoning the invention described and claimed therein and which is hereby and herein reserved and covered.

What I claim as new, and desire to secure 115 by Letters Patent of the United States is—

1. In a device of the class described, a conveyer, a stationary exit landing, and an interposed landing engaging with and controlled by the conveyer. 120

2. In a device of the class described, a conveyer, a stationary exit landing, and an interposed landing supported by the conveyer.

3. In a device of the class described, the combination with a conveyer, of a stationary exit landing, and an interposed substantially horizontal landing supported by the conveyer. 125

4. In a device of the class described, the combination with a moving tread surface, of 130

a stationary exit landing, and an interposed landing maintained in substantially horizontal position by the tread surface.

5. In a device of the class described, the combination with a moving tread surface composed of a series of steps having their treads horizontal at the landing, of a stationary exit landing, and an interposed float supported by each step as it passes the receiving end of the float.

6. In a device of the class described, the combination with a moving tread surface composed of a series of steps, of a stationary exit landing, and an interposed float whose receiving end is adjusted by each step into intimate relation with the tread of such step as the latter passes under the float.

7. In a device of the class described, the combination with a moving tread surface, of a stationary exit landing, and an interposed float resting on the tread surface adjacent the landing.

8. In a device of the class described, the combination with a moving tread surface composed of a series of steps connected to move together with their treads in the same horizontal plane at the landing, of a stationary landing, and an interposed float resting on the treads of the steps adjacent the landing.

9. In a device of the class described, the combination with a moving tread surface composed of a series of steps connected to move together with their treads in the same horizontal plane at the landing, of a stationary landing, and an interposed float resting on the treads of the steps adjacent the landing and having its receiving edge slightly below the under surface of the main portion of the float.

10. In a device of the class described, the combination with tracks, of steps mounted to move thereon and having horizontal treads, and means for driving the steps, of a stationary exit landing, and an interposed vertically movable float resting on the treads of the steps adjacent the stationary landing.

11. In a device of the class described, a moving tread surface composed of a series of steps, a stationary landing, and a float the position of which with relation to each step is automatically determined in advance by such step.

12. In a device of the class described, a moving stairway the steps of which travel with their treads in the same horizontal plane to provide an exit landing at the top of the stairway, a stationary landing, and a float at the stationary landing the position of which with relation to each step is automatically determined in advance by such step.

13. In a device of the class described, the combination with a moving tread surface composed of a series of steps, of a stationary

landing, an interposed float, and means controlled by each step whereby the position of the float with relation to such step is accurately determined in advance by the step.

14. In a device of the class described, the combination with a moving tread surface, of a stationary landing, and an interposed independent float having its receiving edge beveled and resting on the tread surface adjacent the landing. 75

15. In a device of the class described, the combination with a moving tread surface, of a stationary landing, an interposed float between the tread surface and the landing, and swinging supports for said float. 80

16. In a device of the class described, the combination with a moving tread surface composed of a series of steps mounted to move together with their treads in the same horizontal plane at the landing, of a stationary landing, an interposed float between the treads of the steps and the landing, and mechanism interposed between said float and each step for accurately positioning the float vertically with relation to the tread of the step as it reaches the float. 85

17. In a device of the class described, the combination with a moving tread surface composed of a series of steps mounted to move together with their treads in the same horizontal plane at the landing, of a stationary landing, an interposed float between the treads of the steps and the landing, and mechanism for adjusting said float and each step relatively to each other as the step reaches the float. 95

18. In a device of the class described, the combination with a moving tread surface composed of a series of steps mounted to move together with their treads in the same horizontal plane at the landing, of a stationary landing, an interposed float between the treads of the steps and the landing, and mechanism interposed between said float and each step for accurately positioning the float vertically with relation to the tread of the step as it reaches the float, consisting of a lever pivoted to the stationary frame work and having one end coöperating with said step and the other with the float. 105

19. In a device of the class described, the combination with a moving tread surface composed of a series of steps mounted to move together with their treads in the same horizontal plane at the landing, of a stationary landing, an interposed float between the treads of the steps and the landing, and mechanism interposed between said float and each step for accurately positioning the float vertically with relation to the tread of the step as it reaches the float, consisting of a lever pivoted to the stationary frame work at one point and to the forward end of the float at another point, and having the third point thereof coöperating with said step. 110

120

125

130

20. In a device of the class described, the combination with a moving tread surface composed of a series of steps mounted to move together with their treads in the same 5 horizontal plane at the landing, of a stationary landing, an interposed float between the treads of the steps and the landing, and mechanism interposed between said float and each step for accurately positioning the float 10 vertically with relation to the tread surface of the step as it reaches the float, consisting of a lever pivoted to the stationary frame work and having one end coöperating with the float, and the forward end coöperating 15 with an adjustable controlling plate secured on the side of the step.
21. In a device of the class described, the combination with a moving tread surface composed of a series of steps mounted to 20 move together with their treads in the same horizontal plane at the landing, of a stationary landing, an interposed float between the treads of the steps and the landing, and mechanism interposed between said float and 25 each step for accurately positioning the float vertically with relation to the tread of the step as it reaches the float, consisting of a bell crank lever pivoted at its angle to the stationary frame work and pivoted at one 30 end to the float, and having an anti-friction roller mounted on its other end coöperating with an adjustable controlling plate secured on the side of the step.
22. In a device of the class described, the 35 combination with a moving tread surface, of

a stationary landing, an interposed float resting on the tread surface adjacent the landing, and means for balancing the weight of the float to regulate its pressure on the tread surface.

23. In a device of the class described, the combination with a moving tread surface, of a stationary landing, an interposed float resting on the tread surface adjacent the landing, and means for balancing the weight 45 of the float to regulate its pressure on the tread surface, consisting of parallel arms upon which said float is mounted, and an adjustable weight on an extension of one of 50 said arms.

24. In a device of the class described, the combination with a moving tread surface, of a stationary landing, an interposed float resting on the tread surface adjacent the landing, and a counterbalancing arm to regulate 55 the pressure of the float on the tread surface.

25. In a device of the class described, the combination with a moving tread surface, of a stationary landing, an interposed float resting on the tread surface adjacent the landing, and a counterbalancing arm to regulate 60 the pressure of the float on the tread surface and having an adjustable weight thereon.

In testimony whereof I affix my signature in presence of two witnesses.

CHARLES D. SEEBERGER.
